CHEST

Monte L. Levin, New York, N.Y., assignor to Pearl-Wick Corporation, Long Island City, N.Y.

Filed Feb. 18, 1970, Ser. No. 21,494

Term of patent 14 years

Int. Cl. D6—01

U.S. Cl. D33—6

FIG. 1.

FIG. 2.

FIG. 4.

FIG. 5.

FIG. 3.

FIG. 1 is a perspective view of a chest showing my new design;

FIG. 2 is a front elevational view thereof;

FIG. 3 is a rear view thereof;

FIG. 4 is a right side elevational view thereof; and FIG. 5 is a top view thereof.

The design is symmetrical whereby the left side elevational view is similar to the right side elevational view thereof.

I claim:

The ornamental design for a chest, substantially as shown and described.
